Primary Examiner — Paula Allen Greene*(74) Attorney, Agent, or Firm* — Faegre Drinker Biddle & Reath LLP(57) **CLAIM**

The ornamental design for a speaker for an automobile as shown and described.

DESCRIPTION

FIG. 1 is a perspective view of a speaker for an automobile showing my new design;

FIG. 2 is a front view thereof;

FIG. 3 is a rear view thereof;

FIG. 4 is a top view thereof; and,

FIG. 5 is a right side view thereof.

The broken lines depict portions of the speaker for an automobile that form no part of the claimed design.
